UNITED STATES PATENT OFFICE.

JOHN B. GUCKEEN, JR., OF BLUE EARTH, MINNESOTA.

CLOTHES-PIN.

1,234,754.

Specification of Letters Patent. Patented July 31, 1917.

Application filed April 16, 1915. Serial No. 21,683.

To all whom it may concern:

Be it known that I, JOHN B. GUCKEEN, Jr., a citizen of the United States, residing at Blue Earth, in the county of Faribault, 5 State of Minnesota, have invented certain new and useful Improvements in Clothes-Pins; and I do hereby declare the following to be a full, clear, and exact description of the invention, such as will enable others 10 skilled in the art to which it appertains to make and use the same.

This invention relates to improvements in clothes pins, and particularly to wire clothes pins.

15 The principal object of the invention is to provide a simple and novel device of this character which can be manufactured and sold at an extremely low cost.

Another object is to provide a device of 20 this character made of a single piece of wire, the ends of which are conveniently tucked into the twist of the clothes pin so that there will be no projecting sharp ends to injure the fingers or tear the clothes.

25 Other objects and advantages will be apparent from the following description when taken in connection with the accompanying drawing.

In the drawing:

30 Figure 1 is a perspective view of my improved clothes pin showing the first step in forming the same,

Fig. 2 is a perspective view of the second step,

35 Fig. 3 is a perspective view of one side of the complete article, and

Fig. 4 is a perspective view of the opposite side of the complete article.

Referring particularly to the accompanying drawing, 11 represents a large ring and 40 11' the smaller ring, the same being connected by a twisted stem or shank portion 13.

Referring particularly to Fig. 1, it will be seen that the first step in forming these 45 devices consists in taking a piece of wire of suitable length, passing the same around

a pipe 10 so as to form four coils or helix turns 11. The ends of the wire are then twisted together, as shown at 12. The coils are then slipped to the end of the pipe and 50 two of them pulled from the pipe and then bent or swung around until they stand at the side of the pipe in the same plane with the remaining coils.

As shown in Fig. 2, a pipe 13' of slightly 55 smaller diameter than pipe 10 is passed through the two coils at the side of pipe 10. Then, the pipes are turned in opposite directions so that the portions of wire between the coils will be twisted into the form shown 60 in Figs. 3 and 4, thus a clothes pin having two wire loops, 11 and 11' is produced. This twisting of the portions of wire between the coils produces a structure such as shown at 13 in Figs. 3 and 4 wherein the joint 12 is 65 covered and the device can be easily handled without danger of striking the ends of the wire in the fingers or catching the same in the clothes.

From the above the operation of the 70 device will be readily understood, the members of each pair of coils 11 and 11' being adapted to jointly embrace an article upon a clothes line.

The larger ring is provided for use in 75 connection with rope or cord lines while the smaller ring is used for wire lines.

What is claimed is:

A clothes pin formed of a single length of wire including a pair of loops and two 80 connecting strands, one strand being formed of the free end portions of the wire that are twisted together and the other strand being formed by the intermediate portion of the wire which is coiled about the first strand, 85 including said twisted portion.

In testimony whereof, I affix my signature, in the presence of two witnesses.

JOHN B. GUCKEEN, JR.

Witnesses:

D. L. MERSE,
M. E. MASON.
